UNITED STATES PATENT OFFICE

JOSE L. LOPEZ, OF PHILADELPHIA, PENNSYLVANIA

DESIGN FOR A BAG OR SIMILAR CONTAINER

Application filed May 18, 1932. Serial No. 43,840. Term of patent 3½ years.

To all whom it may concern:

Be it known that I, JOSE L. LOPEZ, a citizen of the United States, residing at 4211 Baltimore Avenue, Philadelphia, in the county of Philadelphia and State of Pennsylvania, have invented a new, original, and ornamental Design for a Bag or Similar Container, of which the following is a specification, reference being had to the accompanying drawing, forming part thereof.

I claim:

The ornamental design for a bag or similar container, as shown.

JOSE L. LOPEZ.
